DIVIDED FOUNTAIN

Emory W. Worthington, Chicago, Ill., assignor to
 Goss Printing Press Company, Chicago, Ill., a
 corporation of Illinois

Application November 27, 1944, Serial No. 565,203

16 Claims. (Cl. 101—210)

1

The present invention pertains to improvements in divided ink fountains suitable for use in magazine or other printing presses.

Generally stated, the object of the invention is to provide a divided fountain, that is to say, one having one or more adjustably located partitions for compartmenting the fountain to receive different colors or types of ink, and which embodies a novel and superior arrangement for sealing the same against leakage of ink between adjacent compartments.

More particularly, I aim to provide such an apparatus utilizing long life metal-to-metal type sealing along a major portion of the length of the partition edges which must be sealed, coupled with provision for effectual sealing, through the use of a pad or the like of pliant material, in the zone adjacent the adjustable blade which regulates the thickness of ink film on the fountain roller in such devices.

In a somewhat more specific aspect, it is an object to provide an ink fountain, having an overshot type fountain roller and coating regulating blade, with a novel and effectual arrangement for compartmenting the fountain through use of partitions extending transaxially of the roller and adjustable axially of the same.

The invention also resides in various novel correlations of the elements, and structural improvements therein, by means of which efficient sealing and long life for the apparatus are attained.

Further objects and advantages of the invention will become apparent as the following description proceeds, taken in connection with the accompanying drawings in which:

Figure 1 is a transverse sectional view of a printing press ink fountain embodying the present invention.

Fig. 2 is a fragmentary longitudinal sectional view taken substantially along the line 2—2 in Fig. 1.

Fig. 3 is a fragmentary transverse sectional view through the fountain, taken through one of the adjustable partitions.

Fig. 4 is a detail perspective view of one of the partitions included in the fountain of Figs. 1 to 3.

Figs. 5 and 6 are enlarged detail sectional views taken substantially along the lines 5—5 and 6—6 in Fig. 3.

Fig. 7 is an enlarged fragmentary sectional view of the metal sealing strip coacting with the fountain roller and its associated spring.

The invention is, in its broader aspects, applicable either to overshot or undershot type

2

fountains. Since in its more specific aspects it is, however, particularly applicable to overshot fountains, the type which has incidentally proved most difficult in the past to equip with dividing partitions, the invention has been illustrated herein as applied to the overshot type. It should be understood, however, that even though one particular embodiment of the invention has been illustrated and described in some detail, there is no intention to thereby limit the invention to such particular embodiment. On the other hand, the intention is to cover all modifications, adaptations and alternative constructions falling within the spirit and scope of the invention as expressed in the appended claims.

Referring more particularly to the specific embodiment of the invention illustrated in the drawings for purposes of exemplification, the apparatus there shown (see Figs. 1 and 2) includes an ink fountain or pan 10 of generally trough shape in which an overshot fountain roller 11 revolves. The fountain 10 comprises end plates 12 fixed to a cast body 13 having a flat bottom 14 and inclined flat side faces or walls 15, 16. The purpose of providing a fountain with inclined flat side walls or, in other words, tapering cross section as shown, will appear hereinafter. The fountain roller 11 is journaled in suitable bearings, one of which is indicated at 17 in Fig. 2, located at opposite ends of the fountain; and during operation the roller revolves in a counterclockwise direction (as viewed in Fig. 1).

Extending longitudinally of the fountain roller 11 is a regulating blade 18 which serves to limit the thickness of the film of ink carried by the partially submerged fountain roller 11 to a pickup roller 19. The blade 18 is carried on the underside of a supporting channel 20, the portion of the blade remote from the roller being clamped to the underside of the channel by a retaining strip 21. The usual adjusting screws 22 threaded in the channel or housing 20 and operated by finger pieces 23 bear against the upper side of the blade 18 at equally spaced intervals along the latter's length and serve to flex the blade adjustably toward and from the fountain roller. In the normal operation of the fountain, a body of ink is maintained to a depth indicated generally by the dot-dash line 24 in Fig. 1. As the fountain roller 11 revolves the ink builds up on its trailing side beneath the blade 18, as indicated, and a film of thickness regulated by the blade is carried to the pickup roller 19. It should be observed in passing that the body of ink built up on the roller beneath the blade 18, as a necessary incident to

operation, poses a particularly difficult problem of sealing in that area for any inserted partition.

Pursuant to the aim of the present invention, provision is made for dividing the fountain 10 into separate compartments distributed longitudinally of the fountain roller 11. For that purpose one or more partitions 25 are removably mounted in the fountain in position to extend transaxially of the roller and are adjustable longitudinally of the latter to vary, at will, the size of the several compartments which they define. Since all of the partitions may be identical, a description of one will suffice. In the form shown, the partition 25 is split into upper and lower sections 26, 27, secured together by screws 28 (see Fig. 3). The parting line between the two sections is so located that the lower section embraces slightly less than one-half the circumference of the fountain roller 11, while the upper section extends from the lower section to a point immediately beneath the regulating blade 18.

To secure the partition 25 in place, C-shaped clamps 29 are fixed to its opposite ends and arranged to embrace the marginal or lip portions of the fountain 10. Screws 30 threaded in these clamps engage the undersides of the fountain lips. Upon loosening these screws the partition can readily be slid endwise of the fountain roller to shift the position of the partition.

The partition 25 is made of metal, as is the fountain 10, so that a metal-to-metal seal is afforded between the lower edges of the partition and the abutting surfaces of the fountain. Such edges and surfaces are accurately machined to flat contour, and the fountain is of uniform cross section in a direction axially of the fountain roller 11. Moreover, the exterior of the roller 11 is itself of smooth cylindrical contour. Accordingly, the partitions can be freely slid endwise of the roller and will fit equally well at any point along its length. The tapering cross-sectional shape of the fountain body or, in other words, the provision of outwardly inclined faces 15, 16, makes it possible for the clamp screws 30 to draw the partition down into the fountain with more or less of a wedging action to enhance the sealing effect. On the other hand, when the screws 30 are loosened the partition can readily be freed sufficiently from the surfaces of the fountain to permit adjusting movement of the partition.

A metal-to-metal seal is also afforded between the lower partition section 27 and the fountain roller 11. For that purpose a metal sealing strip 31, resembling a sector of a piston ring, is employed, this strip being curved to conform to the peripheral contour of the fountain roller. The strip 31 is seated in a groove 32 in the edge of the lower partition section 27, being retained against lateral displacement by the side walls of such groove, and the outer end of the strip is overlaid by the tail of the lefthand clamp 29 (see Fig. 3) so as to limit the displacement of the strip in a direction clockwise of the fountain roller. A sheet metal spring 33 of undulatory or wavy shape is interposed between the bottom of the groove 32 and the sealing strip 31 so as to urge the latter into contact with the fountain roller with substantially uniform pressure throughout the length of the sealing strip.

The movement of the regulating blade 18 relative to the fountain roller 11, which is a necessary incident to adjustment of the blade during operation, somewhat complicates the problem of

sealing in the corner of the partition 25 between the blade and roller. To accommodate such movement while still retaining an effectual seal at that point, a pad or strip 34 of pliant sealing material is located in a groove 35 extending about the entire edge of the upper corner portion of the upper partition section 26. Various materials may be used for the pad 34, such, for example, as felt or rubber. In the preferred arrangement illustrated, the pad is laminated, consisting of two strips of felt joined by a layer of synthetic rubber (neoprene). The pliant sealing pad 34 extends from the adjacent end of the metal sealing strip 31 upward about the periphery of the fountain roller to the regulating blade 18, and thence outward beneath the blade for approximately one-half the width of the latter. The pad 34 is sufficiently yieldable that the regulating blade 18 may be flexed without substantial interference and yet the pad is sufficiently resiliant that it remains in contact with the blade, as well as the fountain roller, at all times.

By arrangement of the pliant pad 34 as a single strip supported on a separate section 26 of the partition, replacement of the same is made easy. All that is required is to unscrew the section 26 and put a new strip in the groove 35. Such ease of replacement for this particular part is especially desirable since, of all the sealing elements shown, it is most subject to deterioration, either through wear or loss of resiliency.

The metal strip or sealing ring sector 31 coacts with the pliant pad 34 in retaining the latter in intimate contact with both the fountain roller and regulating blade. As to that, it will be observed (see Fig. 3) that the forward end of the metal strip 31 abuts against the adjacent lower end of the pad. As the fountain roller rotates in its usual counterclockwise direction or, in other words, in a direction to pass the metal sealing ring and pad, in that order, the frictional drag of the fountain roller on the metal strip 31 urges the latter constantly toward the pliant pad. In consequence, the metal strip serves to crowd or urge the pliant pad constantly toward the opposed face of the regulating blade and to buckle it outward slightly toward the roller.

Provision is desirably made for lubricating the contacting surfaces of the seal and fountain roller to prevent sticking or scoring of the latter. For that purpose grease or other suitable lubricant is supplied through a passage 36 in the partition 25 equipped with a conventional supply fitting 37. This passage leads to the groove 32 in which the sealing strip and spring 31, 33 are seated and the grease emerges from this groove through small transverse holes 38 drilled at intervals in the strip 31. A shallow groove 39 in the face of the sealing strip 31 interconnects these holes so as to provide for flow of grease the full length of the strip. Some of the grease presented in this groove is carried by the fountain roller to the face of the pliant pad 34 so that it too is adequately lubricated.

The operation of the disclosed apparatus will in general be clear from the foregoing. By way of brief recapitulation it may be noted that the fountain 10 is equipped with any desired number of partitions 25. In setting up the press for a particular run the clamp screws are loosened and the partitions adjusted to divide the fountain into compartments of desired length. Retightening of the screws clamps the partitions firmly in position. The dividing partitions are located in such manner that inks of various colors or types may be

supplied in the resulting divided portions of the fountain to corresponding portions of the fountain roller and if desired some one or more of the compartments between partitions may be left empty entirely if that width of the press is to be unused.

Having initially set the partitions 25 in desired position any flow of ink past them is effectually prevented since there is a full and effectual seal not only between the partition and fountain body but also between the partition and all portions of the fountain roller 11 and regulating blade 18 which might be contacted by the bodies of ink contained in the successive compartments of the fountain. Other than supplying lubricant from time to time by applying a grease gun to the fitting 37, the sealing apparatus requires no further attention during use, irrespective of changes in adjustment of the regulating blade 18.

I claim as my invention:

1. The combination of a rotatable overshot type fountain roller, a fountain shaped to present a contained body of ink beneath said roller with the roller partially submerged in the body of ink and out of contact with the walls of the fountain, a regulating blade extending along one side of said roller above the normal ink level, a partition extending across the interior of said fountain beneath said roller and rising to a point immediately beneath said blade on said one side of said roller and to a point above the normal ink level on the opposite side, the edge of said partition presented to said roller and blade being closely spaced with reference thereto and having a continuous groove therein extending about the roller periphery concentrically therewith and thence outward of said roller beneath the lower face of said blade, a metal sealing strip shaped as the sector of a ring received in the portion of said groove remote from said blade and partially encircling said roller, means yieldably urging said strip into contact with said roller, a strip of pliant sealing material seated in the remaining portion of said groove and contacting the portions of said roller and blade opposed thereto, the adjacent ends of said sealing strips being abutted together, and the frictional drag of said roller on said metal strip incident to rotation of said roller serving to shove said metal strip endwise along said groove toward said pliant strip and thereby crowd the latter into contact with said roller and blade.

2. The combination of a rotatable overshot type metal fountain roller, a fountain shaped to present a contained body of ink beneath said roller with the roller partially submerged in the ink and out of contact with the walls of the fountain, a regulating blade extending along one side of said roller above the normal ink level, a first partition section extending across said fountain beneath said roller and rising from the bottom of the fountain to a point above the normal ink level on the side of said roller opposite said blade, said partition section being notched out to embrace the periphery of said roller in closely spaced relation throughout not more than half the circumference of the latter, a second partition section detachably secured to the top edge of said first section in alignment therewith beneath said blade and extending in closely spaced relation to said roller about the latter's periphery from said first section upward to a point adjacent said blade and thence outward beneath the lower face of the latter, means forming a metal-to-metal seal between said first partition section and said roller,

and a pad of pliant sealing material interposed between said second partition section and the adjacent portion of said roller as well as the lower face of said blade.

3. The combination of a revoluble fountain roller and an ink fountain therefor presenting a regulating blade to the periphery of said roller, a partition in said fountain extending transaxially of said roller and presenting an edge at least partially embracing said roller in closely spaced relation to the same, said partition including an angular portion extending into the space between said roller and the face of said blade toward which said roller rotates, said partition having a groove in the edge portions thereof presented to said roller, a metal sealing strip seated in said groove and curved to embrace said roller in running contact with the latter and extending to a point spaced from said face of said blade, and a pad of pliant sealing material extending from the end of said metal strip at said point about the edge of said angular portion of said partition in contact with said roller and said face of said blade.

4. The combination of a revoluble fountain roller and an ink fountain therefor presenting a regulating blade to the periphery of said roller, a partition in said fountain extending transaxially of said roller and presenting an edge at least partially embracing said roller in closely spaced relation to the same, said partition including an angular portion extending into the space between said roller and the face of said blade toward which said roller rotates, said partition having a groove in the edge portion thereof adjacent said roller, an arcuate metal sealing strip seated in said groove embracing said roller in running contact with the latter and extending to a point spaced from said face of said blade, a pad of pliant sealing material extending from the end of said metal strip at said point about the edge of said angular portion of said partition in contact with said roller and said face of said blade, and said strip being abutted against the adjacent end of said pad whereby the frictional drag on said strip by said roller incident to rotation of the latter serves to displace said strip endwise toward said pad and retain the latter crowded into contact with both said roller and blade.

5. The combination of a revoluble fountain roller and an ink fountain therefor presenting a regulating blade to the periphery of said roller, a partition in said fountain extending transaxially of said roller and presenting an edge at least partially embracing said roller in closely spaced relation to the same, said partition including an angular portion extending into the space between said roller and the face of said blade toward which said roller rotates, said partition having a continuous groove in the edge portion thereof extending about said roller and beneath said blade, an arcuate metal sealing strip seated in said groove embracing said roller and extending to a point spaced from said face of said blade, an undulatory spring interposed in said groove beneath said strip for yieldably urging the latter into running contact with said roller with substantially uniform pressure throughout the length of said strip, an elongated pad of pliant sealing material also seated in said groove and extending from the end of said metal strip at said point about the edge of said angular portion of said partition in contact with said roller and said face of said blade, and said strip

being abutted against the adjacent end of said pad whereby the frictional drag on said strip by said roller incident to rotation of the latter serves to displace said strip endwise toward said pad and retain the latter crowded into contact with both said roller and blade.

6. The combination of a revoluble fountain roller and an ink fountain therefor presenting a regulating blade to the periphery of said roller, a partition in said fountain extending transaxially of said roller and presenting an edge at least partially embracing such roller in closely spaced relation to the same, a pad of pliant sealing material interposed between said partition edge and said roller on the side of said blade toward which the roller rotates and with said pad extending into contact with the adjacent face of said blade, and means subjected to frictional drag from the periphery of said roller in the course of the latter's rotation for constantly urging said pad toward said blade.

7. In an ink fountain equipped with a revoluble fountain roller, the combination of a compartmentation partition dimensioned for insertion in the fountain transaxially of the roller and presenting a curved edge contoured to conform to the periphery of the roller and partially embracing the latter in closely spaced relation to the same, said edge of said partition having a groove therein extending along the same circumferentially of the roller, a metal sealing strip received in said groove and fashioned as a sector of a ring curved in conformity with the periphery of the roller, and resilient means lying within said groove behind said sealing strip for applying pressure radially inward and bearing against said strip along substantially the entire length thereof so that said strip is squeezed radially into firm running contact with the roller.

8. In an ink fountain equipped with a revoluble fountain roller, the combination of a compartmentation partition dimensioned for insertion in the fountain transaxially of the roller and presenting a curved edge contoured to conform to the periphery of the roller and partially embracing the latter in closely spaced relation to the same, said edge of the partition having a groove therein extending along the same circumferentially of the roller, an arcuate metal sealing strip in the form of a sector of a ring received in said groove and conforming in curvature with the periphery of the roller, means including a spring of undulatory shape lying in said groove beneath said strip and extending substantially the full length of the latter for applying substantially equal forces radially inward at spaced points along said strip and for yieldably urging such strip into firm running contact with the roller and with substantially uniform pressure between roller and strip throughout the length of the latter.

9. The combination of an ink fountain having a revoluble fountain roller, at least a portion of the surface of said roller being of smooth uninterrupted cylindrical shape, a divider partition in said fountain positioned transaxially of the roller and slidably adjustable in position in the fountain in a direction axially of said roller throughout substantially the length of said smooth portion of the latter, means for releasably retaining said partition in various adjusted positions therefor, the edge of said partition presented to said roller having an arcuate notch therein conforming to the curvature of the roller periphery and spaced from the latter, said edge

of the partition being grooved circumferentially of the roller, a metal sealing strip received in said groove and fashioned as a sector of a ring curved to embrace the portion of the roller presented thereto, and resilient means lying within said groove behind said sealing strip, said resilient means providing a plurality of pressure-exerting portions in contact with said strip at spaced points therealong and independently exerting pressure radially inward, so that said strip is urged radially into firm running contact with said roller throughout the length of the strip.

10. The combination of an ink fountain having a revoluble fountain roller, at least a portion of the surface of said roller being of smooth uninterrupted cylindrical shape, a divider partition in said fountain positioned transaxially of the roller and slidably adjustable in position in the fountain in a direction axially of said roller throughout substantially the length of said smooth portion of the latter, means for releasably retaining said partition in various adjusted positions therefor, the edge of said partition presented to said roller having an arcuate notch therein conforming to the curvature of the roller periphery and spaced from the latter, said edge of the partition being grooved circumferentially of the roller, a metal sealing strip received in said groove and fashioned as a sector of a ring curved to embrace the portion of the roller presented thereto, and means including a spring of undulatory shape lying in said groove beneath said strip and extending substantially the full length of the latter for applying substantially equal forces radially inward at spaced points along said strip and for yieldably urging such strip into firm running contact with the roller throughout its length and in all positions of adjustment of said partition longitudinally of said roller.

11. The combination of a generally trough-shaped ink fountain having an overshot fountain roller rotatable therein, said fountain presenting a pair of opposed downwardly and inwardly sloping flat side walls and the interior of said fountain being of uniform cross section in a direction axially of said roller, a transverse partition disposed in said fountain for positional adjustment axially of said roller and extending beneath said roller and rising on each side thereof above the normal ink level, the lower edge of said partition being shaped to extend between the interior walls of said fountain and to fit snugly against them, yieldable means for sealing the edge of said partition presented to said roller against the leakage of ink between said edge and said roller, and releasable clamping means carried by said partition and engageable with said fountain for wedgingly forcing said partition downwardly with reference to said sloping walls of said fountain.

12. The combination of a generally trough-shaped ink fountain having an overshot fountain roller rotatable therein, a regulating blade extending along one side of said roller above the normal ink level, said fountain presenting downwardly and inwardly sloping flat side walls and a flat bottom wall, the interior of said fountain being of uniform cross section in a direction axially of said roller, a transverse partition disposed in said fountain for positional adjustment endwise of said roller, said partition extending beneath said roller and rising on each side thereof above the normal ink level and into adjacency to said blade, said partition having a groove in the edge portion thereof adjacent said roller, an arcuate metal sealing strip seated in said groove

in embracing relation to said roller, means yieldably urging said strip into running contact with said roller, a pad of pliant sealing material extending about the corner of said partition at the point of adjacency of blade and roller, the lower edge of said partition being shaped to fit snugly against the interior walls of said fountain, and releasable clamping means carried by said partition and engageable with said fountain for wedgingly forcing said partition downwardly with reference to said sloping walls of said fountain.

13. The combination of a generally trough-shaped ink fountain having an overshot fountain roller rotatable therein, said fountain presenting a pair of opposed downwardly and inwardly sloping flat side walls, a transverse partition in said fountain slidably adjustable endwise of the fountain, said partition being of wedge-shaped configuration registering with and bridging said opposed sloping side walls, clamping means for pressing said partition downward into the fountain into tight sealing engagement with the latter, and sealing means carried by the edge portion of said partition presented to the roller and partially embracing the latter for preventing the leakage of liquid along said roller past said partition, said clamping elements engaging the respective ends of said partition so that any tendency of said partition to translate down the associated wall upon tightening of one of said elements to produce jamming engagement at said sealing means is effectively resisted by the remaining clamping element.

14. In an ink fountain equipped with a revolvable fountain roller, the combination of a compartmentation partition dimensioned for insertion in the fountain transaxially of the roller and presenting a curved edge contoured to conform to the periphery of the roller and partially embracing the latter in closely spaced relation to the same, said edge of said partition having a groove therein extending along the same circumferentially of the roller, a metal sealing strip received in said groove and curved in conformity with the periphery of the roller, means for yieldably urging said strip into firm running contact with the roller, said strip having a plurality of transverse holes therein opening into a shallow groove in the face of said strip presented to the roller, and said partition having a lubricant supply passage therein opening into the first-mentioned groove, whereby lubricant from said passage may flow into said first-mentioned groove and through said holes to emerge into said shallow groove in said strip for lubricating the surface of the latter contacting the roller.

15. In an ink fountain equipped with a revolvable fountain roller, the combination of a compartmentation partition dimensioned for insertion in the fountain transaxially of the roller and presenting a curved edge contoured to conform to the periphery of the roller and partially embracing the latter in closely spaced relation to the same, said edge of said partition having a groove therein extending along the same circumferentially of the roller, a metal sealing strip received in said groove and curved in conformity with the periphery of the roller, means for yieldably urging said strip into firm running contact with the roller, said strip having a plurality of transverse holes therein opening to the face thereof presented to the roller, and means for supplying lubricant to said strip for passage of the same through said holes.
16. The combination of a revolvable fountain roller and an ink fountain therefor presenting a regulating blade to the periphery of said roller, a partition in said fountain extending transaxially of said roller and presenting an edge at least partially embracing said roller in closely spaced relation to the same, said partition including an angular portion extending into the space between said roller and the face of said blade toward which said roller rotates, said partition having a groove in the edge portions thereof presented to said roller, a metal sealing strip seated in said groove and curved to embrace said roller in running contact with the latter and extending to a point spaced from said face of said blade, a pad of pliant sealing material extending from the end of said metal strip at said point about the edge of said angular portion of said partition in contact with said roller and said face of said blade, said strip having a plurality of transverse holes therein opening to the face thereof presented to said roller, and means for supplying lubricant to said strip for passage of the same through said holes to lubricate the surface of said strip contacting said roller, the latter serving as an incident to its rotation to carry lubricant from the strip to the surface of said pad contacting said roller.
